HANDLE FOR PLUMBING FITTINGS

Lloyd K. Jones and Martin W. Downey, Morgantown,
W. Va., assignors to Rockwell Manufacturing Com-
pany, Pittsburgh, Pa.

Filed Oct. 30, 1970, Ser. No. 25,742

Term of patent 14 years

Int. Cl. D23—01

U.S. Cl. D23—28

FIG. 1

FIG. 2

FIG. 3

FIG. 1 is a top plan view of a handle for plumbing fittings embodying our new design;

FIG. 2 is a side elevational view thereof; and

FIG. 3 is a bottom plan view thereof.

We claim:

The ornamental design for a handle for plumbing fittings, substantially as shown.
